UNITED STATES PATENT OFFICE.

SETH H. POWERS, OF STANBERRY, MISSOURI.

COMBINED WELL-BORING AND ROCK-DRILLING MACHINE.

SPECIFICATION forming part of Letters Patent No. 738,843, dated September 15, 1903.

Application filed January 31, 1903. Serial No. 141,307. (No model.)

To all whom it may concern:

Be it known that I, SETH H. POWERS, a citizen of the United States, residing at Stanberry, in the county of Gentry and State of Missouri, have invented a new and useful Combined Well-Boring and Rock-Drilling Machine, of which the following is a specification.

My invention relates to a combined boring and drilling machine, and has for its object 10 to provide a simple, compact, and efficient construction and arrangement of parts capable, by the minimum adjustment, of performing the functions of either a boring or a drilling machine, inclusive of those necessary for 15 carrying and emptying an auger after it has become filled with borings, and also to provide efficient means for controlling the elevation and lowering of the auger and drill-tools, either manually or mechanically.

20 A further and important object of the invention is to provide an improved spudding mechanism capable of imparting the desired reciprocatory movement to the drill-tools, and in connection therewith to provide efficient means for varying the stroke of the 25 tools, this portion of the mechanism being so constructed as to allow the gradual feeding of the drill rope or cable.

30 A further object of the invention is to provide simple and efficient means for communicating motion to the spudding and other devices, and also to communicate rotary motion to the supports for the drilling mechanism, whereby rotary motion is communicated to 35 the drill during the spudding operation.

Further objects and advantages of this invention will appear in the following description and the novel features thereof will be particularly pointed out in the appended claims.

40 In the drawings, Figure 1 is a perspective view of a combined drilling and boring machine constructed in accordance with my invention, the parts being adjusted for drilling. Fig. 2 is a partial side view of the same. Fig. 3 is an end view. Fig. 4 is a horizontal section on the plane indicated by the line 4-4 of Fig. 2. Fig. 5 is a detail view of a portion of the master-gear or endless rack. Fig. 6 is a detail view in perspective of one of the 45 brake devices. Fig. 7 is a similar view of an auger-holding clamp-jaw. Fig. 8 is a detail view of the clutch employed for connecting

the members of the drive-shaft. Fig. 9 is a similar view of the spudding - drum and attachments. Fig. 10 is a similar view of the lock for the bull - wheel gear. Fig. 11 is a similar view of the locking means for the manually - operated bull - wheel - rotating devices. Figs. 9^a, 9^b, and 9^c are detail views, respectively, of the spudding - drum and its attachments separated.

Similar numerals of reference indicate corresponding parts in all the figures of the drawings.

The supporting-frame of the apparatus embodying my invention preferably consists of a portable base having parallel side beams 1, terminally supported by wheeled trucks and transverse connecting-bars 2, and supported by this base is a turn - table or platform 3, provided with carrier wheels or rollers 4 to traverse a circular track 5, consisting of an internal flange formed on a horizontal master-gear 6, which is bolted permanently to the base. The turn-table or platform is provided with a central opening 7, through which the drilling and boring operations are performed. Rising from the turn-table is a derrick or frame, which preferably includes front and rear pairs of transversely-opposite upwardly-convergent uprights 8 and 9, connected at their upper ends by a cross-bar 10, said front and rear uprights being preferably connected in pairs by longitudinal horizontal braces 11, upon which are stepped the lower ends of standards, each of which is of sectional construction and comprises an upper movable member 12 and a lower fixed member 13. The sections of the standards are secured together by mating bracket-plates 14, having contiguous ears 15, connected by bolts. The standards are connected at their upper ends by a cross-piece 16 and at an intermediate point by a cross-rod 17, upon which is mounted a pulley or guide 18. In addition to this main frame I also employ an auxiliary side frame, including uprights 19, connected with the main frame by means of braces 20, and at the opposite side of the main frame I have also shown a secondary upright 21, suitably braced and connected with the contiguous main upright 8. It will be understood, however, that the specific arrangement of the auxiliary framing members may be varied to suit the

operative parts which are to be supported thereby, but that the described construction has been designed to accomplish the desired objects with the minimum expenditure of material and in order to secure a desirable compactness of structure.

Extending transversely of the frame and mounted in suitable bearings thereon is a main shaft 22, adapted to receive motion from a driving-shaft 23, which is mounted vertically upon the frame and is provided with a bevel-gear 24 to mesh with a corresponding gear 25 on the main shaft. This driving-shaft is of sectional construction, with its lower member 23^a carrying a pinion 26, which is permanently in mesh with the peripheral teeth of the master-gear 6 for continuous operation during the rotary movement of the turn-table or platform, the latter being actuated by any suitable means, as by horse-power, for which purpose it is provided with a sweep 27 and other means for connecting draft-animals thereto. In practice I also prefer to employ an idle pinion 26^a for permanent engagement with the master-gear and having its spindle suitably mounted in bearings on the turn-table or platform at a point diametrically opposite to the operating pinion 26. The upper member 23^b of the driving-shaft carries the above-described bevel-gear 24, and in order that the driving-shaft members may be connected for the communication of motion from the lower member to the upper member I provide a clutch consisting of an axially-fixed member 28 on the shaft member 23^a and an axially-movable clutch member 29 feathered or otherwise fitted for adjustment upon the shaft member 23^b. In the construction illustrated the movable or adjustable clutch member 29 is fitted upon a squared portion of the shaft member 23^b and is connected by a link 30 with a hand-lever 31, suitably fulcrumed upon the frame, preferably the auxiliary side frame 19, in operative relation with a clip or other holding device 32, with which the hand-lever may be engaged when the clutch members are disengaged.

Also mounted in suitable bearings upon the frame parallel with the main shaft is a counter-shaft 33, operatively geared to the main shaft, as by a sprocket-chain 34, traversing sprocket-wheels 35 and 36, secured, respectively, to the main and counter shafts. This counter-shaft forms one member of the spudding apparatus and carries a spudding-drum 37, consisting of parallel disks provided with transversely opposite openings 38 for the reception of a transverse pin 39, said pin serving as the means of attachment of a spudding-chain 40 to the drum. This chain is connected with a movable or traveling pulley 41, traversed by a drill-rope, as hereinafter fully explained. Secured to one or both sides of the spudding-drum is a cam 42, forming one member of a clutch, whereby motion is communicated from the counter-shaft 33 to the

drum, the latter being loosely mounted upon its shaft for alternate revoluble movement in opposite directions. The other clutch member consists of a clutch-arm 43, pivotally mounted upon a bracket-arm 44, which is fixed to said shaft, the clutch-arm being preferably provided with a terminal pin 45, carrying an antifriction-roll 46 or the equivalent thereof for contact with the face of the clutch member 42. The bracket-arm 44 is preferably bifurcated, as shown, to receive the clutch-arm, and the latter is extended beyond its fulcrum-point to form a trip-arm 47, adapted for contact with the platform or other fixed smooth-surfaced portion of the mechanism in order to disengage the shaft clutch member 43 from the drum clutch member 42 and allow the return movement of the drum after the latter has completed a predetermined angular movement in a forward direction. The clutch-arm is yieldingly held in its normal position by means of an actuating-spring 48, coiled upon a guide-pin 49, which extends through a guide-opening 50 in the trip-arm, the opposite end of said guide-pin being secured to a projecting shouldered portion 51 of the bracket-arm. The solid-line arrow in Fig. 9 indicates the direction of forward rotation of the clutch-arm-carrying devices and the dotted arrow in the same figure the return movement of the drum after the release of the clutch member 42 by the displacement of the clutch-arm.

The main drill-rope 52 extends from a drum or bull-wheel 53 to and over a pulley 54, located near the upper end of the derrick, thence to the running or movable pulley 41, again upwardly to the top of the derrick, and over a second pulley 55, and is attached to the upper end of a drill-tool 56 of any suitable or preferred construction, and it will be seen that the continuous rotation of the counter-shaft 33 during the revolution of the turn-table or platform will communicate motion from the clutch-arm 43 to the spudding-drum and carry the same around, thereby drawing upon the chain 40 and elevating the drill-tools until the trip-arm comes in contact with a fixed object, when the release of the drum will allow the drill-tools to drop. By placing the pin 39 in different alined openings of the spudding-drum the length of stroke of the running pulley 41 before the release of the drum from the clutch-arm may be varied to suit the conditions under which the machine is operated.

In order to control the operations of the bull-wheel and provide for the elevation of the drill-tools by the winding of the drill rope or cable 52, I employ a gear 57, fixed to the spindle 58 of the bull-wheel, and a shifting pinion 59, mounted upon the feathered or squared portion of the main shaft and adapted to be thrown into or out of the plane of the gear 57 in order to communicate motion to the bull-wheel or allow the free rotation thereof, as may be preferred. When it is desired to ele-

vate the drill-tools by the winding of the cable 52 upon the drum or bull-wheel, the spudding device is first disconnected from the main shaft or is thrown out of gear in any suitable manner, as by the removal of the sprocket-chain 34, and the pinion 59 is moved into engagement with the gear 57 to communicate motion to the drum-shaft 58. When it is desired to relower the tools, the members 10 of the driving-shaft clutch should be disengaged to permit the opposite rotary movement of the main shaft, and the rapidity of descent of the tools may be controlled by means of a brake fitted upon the main shaft and consisting of a drum 60 and opposite brake-shoes 61 and 62, properly constructed to fit opposite sides of the drum and carried, respectively, by a pivotal arm 63 and a brake-lever 64, which are hinged together at their remote ends, as 15 shown at 65. It is obvious that by depressing the brake-lever or moving its free end toward the pivotal arm 63 the brake-shoes will be forced into contact with the surface of the drum to impede to a greater or less extent the 20 rotary movement of the shaft. It is also desirable for the manipulation of smaller tools or for raising and lowering the tools short distances to employ manual means requiring no particular adjustment of the parts, and 25 hence I employ a crank-shaft 66, suitably mounted upon the frame and having a terminal key-seat to receive a crank-arm 67, an operating-gear 68, carried by said crank-shaft, and a gear 69, carried by the bull-wheel 30 shaft 58. The gears 68 and 69 may be connected for operation to communicate motion from the crank-shaft to the bull-wheel shaft by means of an intermediate pinion 70, loosely fitted upon the main shaft 22 for movement 35 into and out of the plane of said gears. This pinion 70 may be locked at any desired adjustment to correspondingly hold the bull-wheel by means of a latch 71, mounted to slide 40 in a suitable guide 72 on the frame and having an operating hand-lever 73, said latch being 45 adapted to engage between the teeth of the pinion; but as a means of locking the bull-wheel against rotary motion and for facilitating the gradual feeding thereof during the 50 drilling or spudding operation I employ, in connection with the gear 69, a locking device, including a bolt 74, mounted for movement radially with relation to said gear and spring-actuated, as by a coil-spring 75, arranged upon 55 a guide-pin 76, said bolt having one extremity arranged in operative relation with the teeth of the gear 69 and having the other end outwardly turned to form a step 77, upon which the foot of the operator may be arranged to 60 disengage the bolt from the wheel. In connection with the bolt I employ a latch 78, adapted to hold the bolt in its inoperative position and having a terminal shoulder 79 to bear upon the foot-rest 77. 65 In connection with the above-described mechanism I also preferably employ an auxiliary cable 80, adapted for lowering auxil-

iary or additional lengths of drill-tools into the hole for connection with those already in operation and also for elevating an auger 70 preparatory to the emptying thereof, and hence I have illustrated a drum 81, of which the spindle 82 is mounted in suitable bearings on the frame and carries a shifting gear 83, mounted upon a feathered or squared portion of the spindle and adapted for movement into and out of the plane of a gear 84, carried by the main shaft. This drum or auxiliary bull-wheel shaft is fitted with a brake device having a lever 84^a and constructed 75 identically as hereinbefore described in connection with the brake upon the main shaft. Said lever is used in connection with a clip 85, whereby the auxiliary drum may be locked against rotation during the operation 85 of the drilling mechanism. The auxiliary rope or cable extends over the hereinbefore-described pulley 18, mounted upon the transverse rod 17 of the derrick, and in the drawings it is shown attached to a drill-rod section 56^a. The extremity of the shaft 82 is also constructed to form a wrench-seat in order that the auxiliary drum may be manually operated. 90

It will be seen from the foregoing description that from the main shaft, which is actuated directly by a driving-shaft, of which one member is in permanent mesh with the fixed master-gear, I am enabled to communicate motion simultaneously or independently to 100 either the spudding-drum shaft or the several drum-shafts and that by means of the shifting devices referred to it is possible to change the connection of the main shaft with the other members without loss of time or to 105 wholly disconnect the main shaft from the other parts of the device in order to check the motion thereof or to release said other members for the paying out of the connected cables. 110

In addition to the parts already described, however, I have provided simple means for adapting my machine for boring, and in this connection I provide an auger holder or clamp 86, arranged for vertical movement upon the 115 frame supported by the platform or turn-table, but designed to engage the auger and communicate motion thereto from the rotary platform. In the construction disclosed this auger holder or clamp, which is illustrated in detail in Fig. 7, consists of coöoperating correspondingly-constructed members 86^a and 86^b, having longitudinal slots 87 and interlocking inner ends or jaws adapted to engage the auger-shank 88. Said slots receive 120 vertical guides 89, extending upwardly from the platform to horizontal braces 90, connecting the front and rear uprights 8 and 9 of the derrick, and the holder members are thereby adapted for either longitudinal or vertical 125 movement to suit the movements of the auger, but are held from lateral movement, whereby as the platform rotates the jaws communicate motion to the auger and accomplish 130

the boring operation. The specific construction of holder-jaws illustrated in the drawings embodies a tongue 91 on each member for engagement with a seat or loop 92 on the other member, the tongue and seat or loop of each member being exposed perpendicularly to each other, whereby when the jaws of the two members are connected they form an angular opening in which the shank of the auger is held from rotation.

It will be understood that any ordinary construction of auger may be used in connection with the apparatus, and during the boring operation the superstructure of the derrick, including the standard members 12 and the pulleys 18, 54, and 55, may be removed.

The means for raising the auger when filled consists of a crane 93, mounted at its lower end in a suitable socket in the platform and at its upper end in a bearing in a bracket 94, extending horizontally from the main or lower portion of the derrick-frame. In the construction illustrated this bracket consists of angularly-disposed rods having registering loops at their outer ends to form the above-mentioned bearing and provided at their inner ends with hooks 95, which engage eyes 96 in arms 97, projecting rearwardly from the derrick-frame. It will be understood that this crane may be readily dismounted or replaced, according to whether the machine is to be used for boring or drilling, and in Fig. 1 I have shown suspended thereon an auger 98, as seen when withdrawn from the hole and swung outward beyond the platform for emptying. It will be understood that the auxiliary cable 80 may be employed for this purpose, as indicated by the dotted lines 80^a in Fig. 1, the auger being elevated by means of said cable and engaged with the terminal hook 99 of the crane, after which the latter is swung, as indicated in said Fig. 1, to discharge the borings.

From the above description it will be seen that the machine embodying my invention is compact and includes all of the mechanism necessary for either boring or drilling and that the adjustment of the members to suit it for either purpose may be accomplished with the minimum loss of time and exertion upon the part of the operator, whereby the machine may be controlled by the aid of the minimum number of attendants, and, furthermore, that in practice various changes in the form, proportion, and the minor details of construction may be resorted to without departing from the spirit or sacrificing any of the advantages of this invention.

Having described my invention, what I claim is—

1. A combined boring and drilling machine having a stationary annular master-gear, a revoluble platform carrying drilling mechanism and operatively connected with the master-gear, and an auger-holder carried by the platform and having detachable members mounted for relative longitudinal movement

and having inner interlocking jaws, substantially as specified.

2. A combined boring and drilling machine having a stationary master-gear, a revoluble platform carrying drilling mechanism and operatively connected with the master-gear, and an auger-holder carried by the platform and having longitudinally-slotted members, fixed guides upon the platform engaging said slotted members, said members being provided at their inner ends with interlocking jaws, substantially as specified.

3. A combined boring and drilling machine having a stationary master-gear, a revoluble platform carrying drilling mechanism and operatively connected with the master-gear, and an auger-holder carried by the platform and having longitudinally-slotted members, fixed vertical guides on the platform engaging said slotted members, the inner ends of said members having interlocking jaws, substantially as specified.

4. A combined boring and drilling machine having a stationary master-gear, a revoluble platform carrying drilling mechanism and operatively connected with the master-gear, and an auger-holder carried by the platform and having separable members mounted for vertical and horizontal sliding movement, each member being provided at its inner end with a longitudinal tongue and a lateral keeper or eye for the reception of the tongue of the other member, said tongue and eye being angularly disposed, whereby when the jaws are interlocked they form a seat to receive an auger, substantially as specified.

5. In a machine of the class described, the combination with a fixed master-gear and a revoluble platform carrying a suitable framework, of a sectional driving-shaft having one of its members provided with a pinion in permanent mesh with the master-gear, clutch mechanism for connecting the sections of the driving-shaft, a main shaft operatively geared with the other member of the driving-shaft, a bull-wheel shaft having a gear, a pinion mounted for adjustment upon the main shaft and adapted to be arranged in engagement with said gear on the bull-wheel shaft, and brake mechanism in operative relation with the main shaft, and manual means for operating the bull-wheel shaft, the same including a crank-shaft carrying a pinion, a gear on the bull-wheel shaft arranged in the plane of said pinion, and an adjustable pinion mounted upon the main shaft for axial movement into and out of the plane of said pinion and gear, substantially as specified.

6. In a machine of the class described, the combination with a continuously-revolvable shaft and means for operating the same, of a spudding-drum loosely mounted upon the shaft, a cam carried by the drum, a bracket-arm fixed to the shaft, a clutch-arm pivotally mounted upon the bracket-arm and having a pin arranged in the path of said cam, yielding means for holding said clutch-arm in its

operative position, and a trip-arm consisting of an extension of the clutch-arm and having a fixed object arranged in the path thereof to disengage the clutch-arm from the cam, substantially as specified.

7. In a machine of the class described, the combination with a continuously-movable shaft and means for communicating motion thereto, of a spudding-drum loosely mounted upon the shaft and having an adjustable transverse pin for the connection of the spudding-chain, and clutch mechanism for periodically locking the spudding-drum upon said shaft and releasing the same for reverse movement, said mechanism including a drum member, a pivotal-shaft member consisting of a spring-actuated arm having a pin arranged in the path of the drum member, and a trip-arm connected with the clutch-arm and disposed in operative relation with a fixed object to disengage the clutch-arm from the drum member, substantially as specified.
8. In a machine of the class described, the combination with a stationary master-gear, a revolute platform, a sectional driving-shaft having one member provided with a pinion in permanent mesh with the master-gear, a main shaft operatively geared with the other member of the driving-shaft, and clutch mechanism for connecting and disconnecting the driving-shaft members, of a spudding-drum shaft, connections between the spudding-

drum shaft and the main shaft, a bull-wheel shaft, operating connections between the bull-wheel shaft and the main shaft including an axially-adjustable gear mounted on one of said shafts, a second gear carried by the bull-wheel shaft, and locking devices in connection with said second gear for checking the revolute movement of the bull-wheel shaft, substantially as specified.

9. In a machine of the class described, the combination with drilling mechanism including a main shaft, a spudding-shaft geared to the main shaft, main and auxiliary drum-shafts, gearing for connecting said drum-shafts with the main shaft, and each including an axially movable or shiftable gear, brake devices for the main shaft and the auxiliary drum-shaft, manually-operable means for rotating the main drum-shaft, and including a shifting pinion adapted to be arranged in the plane of gears respectively on a crank-shaft and the main drum-shaft, and a locking device, including a bolt for engaging said shifting pinion, substantially as specified.

In testimony that I claim the foregoing as my own I have hereto affixed my signature in the presence of two witnesses.

SETH H. POWERS.
